(57) **CLAIM**

The ornamental design for a portion of a tenderizer, as shown and described.

DESCRIPTION

FIG. 1 is a top perspective view of a portion of a tenderizer incorporating the new design, shown in environmental use, shown in a reduced scale;

FIG. 2 is a top perspective view thereof;

FIG. 3 is a side view thereof;

FIG. 4 is a bottom perspective thereof;

FIG. 5 is a bottom plan view thereof; and,

FIG. 6 is a top plan view thereof.

The broken lines in the figures illustrate portions of the portion of a tenderizer which form no part of the claimed design. The broken needles in FIG. 1 depict environmental subject matter only and form no part of the claimed design.
